UNITED STATES PATENT OFFICE.

GLEN A. BRUNSON, OF ALGONA, IOWA.

PIPE-CLEANER.

1,246,710.

Specification of Letters Patent. Patented Nov. 13, 1917.

Application filed April 5, 1917. Serial No. 159,950.

To all whom it may concern:

Be it known that I, GLEN A. BRUNSON, a citizen of the United States, residing at Algona, in the county of Kossuth and State 5 of Iowa, have invented certain new and useful Improvements in Pipe-Cleaners; and I do declare the following to be a full, clear, and exact description of the invention, such as will enable others skilled in the art to 10 which it appertains to make and use the same.

This invention relates to cleaning devices to be used more particularly for cleaning smoking pipes, but which may be just effectively used for cleaning tubes or the like.

One object of the invention is to provide a cleaning device which may be carried as part of the personal paraphernalia of the user the same as a fountain pen, lead pencil 20 or the like.

Another object of the invention is to provide a cleaning device of this character which does not have to be thrown away after one use, as is the case with most pipe 25 cleaners now on the market.

A further object of the invention is to provide a device of this character which will be extremely simple, strong, durable and inexpensive in construction, and which will 30 be efficient and reliable in operation, and well adapted to the purpose for which it is designed.

With these and numerous other objects in view, the invention consists of certain novel 35 features of construction and the combination and arrangement of parts as will be herein-after fully described and claimed.

In the accompanying drawings forming a part of the application and in which similar 40 reference characters designate like parts throughout the several views:

Figure 1 is a side elevation of a device constructed in accordance with this invention;

Fig. 2 is a central longitudinal sectional view through a smoking pipe illustrating the manner in which the invention is used 45 for cleaning the same;

Fig. 3 is a central longitudinal sectional 50 view of the cleaner proper disposed in its holder or casing;

Fig. 4 is a similar view illustrating the manner in which two cleaners may be carried in a single casing;

Fig. 5 is an enlarged perspective view of 55 one end of one form of cleaner;

Fig. 6 is a similar view of a modified form of cleaner; and

Fig. 7 is an enlarged perspective view of 60 one end of the form of cleaner shown in Fig. 5, illustrating the manner in which the cleaning material is connected and applied to the same.

Referring more particularly to the drawings, the reference numeral 1 designates a 65 tubular casing which is very much similar to the combination pen and pencil holders now on the market in that into the ends of the tube are fitted caps or plug members 2. In Fig. 3 of the drawings one of the plug 70 members 2 has embedded therein one end of a cleaner 4. This cleaner 4 consists of a small pliant wire of rectangular shape in cross section and has its free end flattened as at 5. The length of the wire 4 is to be 75 sufficient so that it may be inserted completely through the aperture through a pipe stem.

The reference numeral 6 designates a 80 notch formed at the extreme end of the flattened portion of the wire and the numeral 7 designates another notch formed in one side edge of this flattened end of the wire. As clearly shown by the drawings, the notch 85 7, which is substantially V-shaped, is arranged angularly with respect to the edge of the flattened end of the wire and inclines toward the notch 6.

In using a device constructed as just described, an ordinary piece of cord *a* is looped 90 in the two notches 6 and 7 and then twisted around the wire. This cord *a* forms the cleaning element proper and is capable of absorbing practically all of the nicotine contained in the pipe stem. The wire having 95 the cord thus fixed or connected to its free end is inserted in the aperture in the pipe stem *b* as shown in Fig. 2 and moved back and forth, turned, or both to accomplish the desired result, the notches 6 and 7 preventing the cord from becoming disengaged 100 from the end of the wire during this oper-

ation. Obviously, when the cord *a* has served its purpose, it may be thrown away and substituted by new clean pieces.

In Fig. 6 of the drawings, the wire 4 is of circular configuration in cross section instead of being rectangular as in the form above described.

It may be desirable to carry two cleaners in a single holder and in that case, both of 10 the plug members 2 are provided with such cleaners as shown in Fig. 4 of the drawings. If desired, one of the cleaners may be of different construction than that shown in Figs. 5 and 6 of the drawings.

15 From the foregoing description, taken in connection with the accompanying drawings, the construction, use and operation of the device will be readily understood, without a more extended explanation. It will be 20 seen that the objects of the invention have been effectively carried out as a pipe cleaner has been provided which may be carried at all times by the user and which is practically everlasting.

Copies of this patent may be obtained for five cents each, by addressing the "Commissioner of Patents, Washington, D. C."

As various changes in form, proportion, 25 and in the minor details of construction may be resorted to without departing from the spirit of this invention, I do not wish to be limited to the precise construction herein shown and described. 30

I claim:—

A device of the class described comprising a wire, a handle member secured to one end thereof, the other end being flattened and provided with a pair of cord loop receiving 35 notches, one of said notches being disposed in the extreme end of said flattened portion, the other notch extending from one edge of the latter and inclined toward the first notch. 40

In testimony whereof I have hereunto set my hand in the presence of two subscribing witnesses.

GLEN A. BRUNSON.
